US0D1046928S

(12) **United States Design Patent** (10) **Patent No.:** **US D1,046,928 S**
(45) **Date of Patent:** **** Oct. 15, 2024**

(54) **BUCKET SHROUD**(71) Applicant: **Caterpillar Inc.**, Peoria, IL (US)(72) Inventors: **Nathan Bjerke**, Peoria, IL (US);
Thomas Marshall Congdon, Dunlap,
IL (US)(73) Assignee: **Caterpillar Inc.**, Peoria, IL (US)(**) Term: **15 Years**(21) Appl. No.: **29/924,515**(22) Filed: **Jan. 19, 2024****Related U.S. Application Data**

(63) Continuation of application No. 29/891,716, filed on May 9, 2023, now Pat. No. Des. 1,018,602, which is a continuation of application No. 29/834,037, filed on Apr. 8, 2022, now Pat. No. Des. 991,986, which is a continuation of application No. 29/785,347, filed on May 25, 2021, now Pat. No. Des. 952,697, which is a continuation of application No. 29/708,298, filed on Oct. 4, 2019, now Pat. No. Des. 927,561.

CAT Shroud <https://parts.cat.com/en/catcorp/339-0310> (Year: 2021).
(Continued)*Primary Examiner* — Mark A Goodwin**CLAIM**

The ornamental design for a bucket shroud as shown and described.

DESCRIPTIONFIG. 1 is a perspective view of a bucket shroud showing our new design;
FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines depict portions of the bucket shroud which form no part of the claimed design.

The dot-dash broken lines depict boundaries which form no part of the claimed design.

1 Claim, 5 Drawing Sheets# US D1,046,928 S
